UNITED STATES PATENT OFFICE.

LEGENDRE CINQ-MARS, OF SAN FRANCISCO, CALIFORNIA.

GAS-HEATER.

1,392,479.

Specification of Letters Patent.

Patented Oct. 4, 1921.

Application filed August 10, 1920. Serial No. 402,717.

To all whom it may concern:

Be it known that I, LEGENDRE CINQ-MARS, a citizen of the United States, residing at San Francisco, in the county of San Francisco and State of California, have invented new and useful Improvements in Gas-Heaters, of which the following is a specification.

This invention relates to improvements in gas heaters of the radiator type which are constructed so as to simulate in appearance the ordinary hot water or steam radiator.

The primary object of this invention is to provide a gas heater of the above-noted type which will be exceptionally simple and inexpensive as to construction, which will provide maximum heat at a relatively low fuel consumption, which will eliminate objectionable odors and overcome the hazard of extinguishing the burner flame in case of back draft or a sluggish flue, and allow immediate circulation.

The invention further consists in a novel construction relative arrangement of parts whereby the heater may be more easily and cheaply manufactured, the construction embodying relatively few parts and being of such arrangement that, possibility of collection of condensation in the heater and loss of heat through the stack are reduced to a minimum.

The invention possesses other advantages and features some of which, with the foregoing will be set forth at length in the following description wherein I shall outline in full that form of the invention which I have selected for illustration in the drawings accompanying and forming a part of the present specification. In said drawings, I have shown one form of the construction of my invention, but it is to be understood that I do not limit myself to such form, since the invention as expressed in the claims may be embodied in a plurality of forms.

Referring to the drawing:

Figure 1 is a front elevation partly broken away and in section of the gas heater of this invention.

Fig. 2 is a vertical sectional view taken on the line 2-2 of Fig. 1.

Fig. 3 is a horizontal view taken on the line 3-3 of Fig. 2.

In the present embodiment of the invention, the heater comprises a plurality of radiator sections joined to one another so as to provide a compact heater structure

such as illustrated in the drawings and which will be more particularly described hereinafter. The end sections 4 of the radiator have supporting legs 5 attached thereto so as to support the structure from the floor. Each radiator section comprises an ascending flue 6 and a descending flue 7, said flues communicating with one another only at the upper ends of the section. The construction of the section preferably embodies the employment of two similar elongated concavo-convex halves 8 which at their peripheries are lap-seamed together as at 9. Centrally of these sections, and vertically, the material of each half is pressed inwardly so that each half contacts with the other and provides a partition 10. The contacting portions are firmly held together by suitable tie rods 11 held in place by nuts 12, said rods being inserted through the pressed-in portion 10. By this construction, I may employ light sheet metal and by reason of the thinness of the metal provide giving off heat very rapidly and to a maximum extent.

In assembling the sections, the tie rods 11 constitute the means for holding the sections together, with spacers to hold the sections apart. The lower ends of the ascending flues 6 of the sections are provided with elongated openings 13 which are formed in outwardly extending bosses 14 on the opposite faces of the sections and these openings provide means of communication between the lower ends of the ascending flues of said sections, forming a burner passage 15 extending horizontally through the lower ends of the ascending flues. A burner pipe 16 is inserted from one side of the radiator into the passage 15 and is provided with burner openings 17 in its upper face, said openings being arranged to produce a flame within the lower end of each ascending flue. Adjacent the lower end of the descending flues in opposed sides thereof are openings 18 communicating with one another whereby a horizontal communicating passage 19 is provided at the lower ends of said descending flues. It will thus be seen that the sections communicate with one another only at the lower ends of the flues in said sections, whereas the upper end of each section is independent of any communication with another section. By providing the bosses 14 on the opposite faces of the sections, the assemblage of the sections in

spaced relation with one another so as to provide for effective heating, is facilitated. This is particularly shown in Fig. 1.

The heat from the flame of the burner 16 passes directly upwardly into the ascending flue 6 of each section and then downwardly through the descending flue of each section, the products of combustion passing through the communicating passage 19, 10 which passage is formed by the openings 18.

I preferably connect an outlet flue 21 with the lower ends of the descending flues of the two center sections 4 as shown particularly in Figs. 2 and 3 of the drawings, said flue 21 being disposed entirely outside of the sections to which it is connected. Doing so overcomes reheating. Preferably, the flue 21 is of rectilinear outline having a horizontal intake passage 22 at its lower 20 end provided by a right-angular extension 23 of the flue. The extension 23 is extended into openings 24 cut in the two center sections of the radiator and the passage 22 thus communicates with the passage 19 and 25 lower ends of the descending flues 7 of said sections. The upper side 23' of the extension 23 is longer than the lower side and extends into the descending flues 7 so as to act as a baffle to prevent too rapid a circulation through the flues, said side 23' particularly blocking the descending flues center of the center sections. The upper end of the flue 21 is closed by a wall 25 and a horizontal outlet opening 26 communicating 30 with an internal screw threaded boss 27 on the outside of the flue is provided in the back wall of said flue. A partition wall 28 is provided in the flue 21 so as to form a main outlet flue passage 29 and a back draft 35 outlet passage 30 extended vertically and parallel to one another. The partition 28 terminates below the outlet opening 26. A baffle plate 31 is provided at the upper end of the passage 29 and extends outwardly 40 from the rear wall of the flue 21, horizontally and at a point below the lower edge of the opening 26, terminating forwardly at a point spaced from the upper end of the partition 28. The flue 21 is provided 45 with a transverse outlet port 32 which communicates with the atmosphere. In case of back draft or sluggish flue, the products of combustion in passing back into the flue 21 will be prevented by the baffle 31 from en-

tering the passage 29 and will pass downwardly through the passage 30 and exhaust into the room through the port 32.

I claim:

1. A gas heater embodying in its construction identically constructed heater sections each of which comprises an ascending flue and a descending flue communicating with one another at their upper ends only, said sections having openings in opposite sides at their lower ends registering and communicating with the corresponding flues of said sections at the lower ends of said flues, a burner extending through the openings which communicate the ascending flues with one another, and an outlet flue located outside of the sections and having its lower end only extended directly into the descending flues of certain sections. 65

2. A gas heater embodying in its construction a plurality of heater sections, a burner in said sections, an outlet flue mounted outside of said sections and having its lower end in communication with certain of the heater sections, said outlet flue comprising a main outlet flue and having a 70 horizontally disposed outlet opening at its upper end, a baffle plate extending above said main outlet flue and below said outlet opening, said flue having a transverse outlet opening at a point intermediate of its 75 ends, and a partition in said flue providing a back draft passage communicating with said outlet openings, said partition terminating at its upper end below said baffle. 80

3. A gas heater embodying in its construction a plurality of heater sections, a burner in said sections, an outlet flue mounted outside said sections, and having a horizontally disposed intake opening communicating with certain of said heater sections, 90 said flue having a horizontally disposed outlet opening adjacent to its upper end and a similar outlet adjacent to its lower end, which latter outlet communicates with the atmosphere, a baffle in said flue extended 95 part-way across the passage therethrough at a point below said first-named horizontal opening, and a partition in said flue providing a passage communicating at its ends with the upper part of the flue and said last- 100 named outlet opening. 105

LEGENDRE CINQ-MARS.
